Primary Examiner — Zenia Bennett(74) Attorney, Agent, or Firm — Day Pitney LLP(57) CLAIM

The ornamental design for a hair piece for a toy figure, as shown and described.

DESCRIPTION

FIG. 1 is a top, front perspective view of our ornamental design for a hair piece for a toy figure;

FIG. 2 is a front view thereof;

FIG. 3 is a rear view thereof;

FIG. 4 is a right side view thereof;

FIG. 5 is a left side view thereof;

FIG. 6 is a bottom plan view thereof;

FIG. 7 is a top plan view thereof;

FIG. 8 is a top right perspective view thereof; and,

FIG. 9 is a bottom, front perspective view thereof.

The broken lines in each of the figures are for environmental purposes only and form no part of the claimed design.
